ENVELOPE AND BAG FASTENER

Irene W. Mabry, De Land, Fla.

Application July 14, 1938, Serial No. 219,236

4 Claims. (Cl. 229—77)

This invention relates to an improved fastening means for envelopes, bags and paper receptacles of similar type.

It is an aim of this invention to provide an improved fastener for envelopes and bags in particular, which may be formed of paper including corresponding fastening elements adapted to be passed through a slot in the bag or envelope flap and to be bent outwardly to retain the flap in a closed position.

More particularly, it is an object of this invention to provide fastening elements having means whereby they will retain the flap in a closed position even when disposed in a position to disengage said flap to prevent the container from being accidentally opened.

Other objects and advantages of the invention will hereinafter become more fully apparent, from the following description of the drawing, which illustrates a preferred form of the invention, and wherein:

Figure 1 is a side elevational view of the back of a conventional envelope, shown in an open position, and having a fastener constructed in accordance with this invention attached thereto.

Figure 2 is a fragmentary side elevational view showing the flap of the envelope in a closed position and in engagement with the fastener.

Figure 3 is a horizontal sectional view taken on the line 3—3 of Figure 2.

Figure 4 is a vertical sectional view taken through the center of the envelope showing the fastener in elevation, immediately after it has been inserted through the slot on the envelope.

Figure 5 is a detailed elevational view showing the blank cut and prepared to be bent to form the fastener, and

Figure 6 shows the reinforcing member attached to the flap of the envelope and slotted to reinforce the envelope slot.

Referring more particularly to the drawing, wherein like reference characters designate like or corresponding parts throughout the different views, 10 designates generally an envelope provided with a flap 11 having a slot 12 formed therein, transversely of the flap and intermediate of its ends. The envelope, as illustrated, is of conventional form except for the slot 12 and is shown merely to illustrate the application of the fastener designated generally 13, and it is to be understood that the invention is not intended to be limited in its use to an envelope, as it is equally well adapted for use with bags and other forms of flat receptacles or containers.

The fastener 13 is preferably formed from a

single strip of fibrous material such as paper, which is cut to form the two end members 14 and the intermediate portion 15, which is adapted to be folded along the line 16 so that an end member 17 is positioned against an intermediate member 18 to form the two fastening members 19. Members 17 and 18 are cut along their upper edges to form the inclined portions 20, and on their lower edges are cut to form the converging points 21. The sides of the points 21 of the members 17, which connect with the end members 14 are elongated to extend above the corresponding side of the other points as indicated at 22 for a purpose which will hereinafter be described.

Portions 17 and 18 when assembled form the members 19, and may be adhesively secured together and will normally assume the position as seen in Figure 1. When thus positioned, the end members 14 will be disposed relatively close to each other to form a base, and are adapted to be secured to the outer side of the back of the envelope 10 by means of an adhesive.

A reinforcing member 23, as best seen in Figure 6, is provided with a slot 24 and is adapted to be secured to the inner side of the flap 11 with the slot 24 in alignment with the slot 12 to reinforce slot 12.

The flap 11 which normally folds along the line 25, is folded over toward the fastening member 19 and pulled downwardly, to temporarily fold or bend below the line 25 so that the lower end of the slots 12 and 24 may pass the end 21 as the members 19 pass through said slots, after which flap 11 is released to return to its normal folding line 25 thereby raising the flap 11 to the position 35 as seen in Figure 4 so that the points 21 will prevent the flap from being opened until it is again pulled downwardly. The inner sides of the points 21 of the fastening members 19 being longer, as indicated at 22 permits flap 11 to raise to its normal position, as indicated by the line 25, or even beyond this position, should envelope 10 be filled to capacity, without exerting pressure on the lower ends of slots 12 and 24 which might cause them to tear. The inclined upper edge 20 is provided to accommodate the upper edges of the slots 12 and 24 when flap 11 is pulled downwardly to pass the points 21. After flap 11 has reached the position as seen in Figure 4, the fastening members 19 are folded outwardly on the center fold line 16 to lie flush against the outer side of the flap 11, as seen in Figure 3, and the envelope 10 is then ready for transmittal. When it is necessary to open the envelope, members 19 are returned to the position as seen in Figure 4, and 55

- the flap 11 is pulled downwardly and outwardly so that the slots 12 and 24 at their lower end may be passed beneath the points 21 to disengage the flap and permit the envelope 10 to be opened.
5. Fastener 13 is obviously equally well adapted for use with bags and other similar forms of containers or receptacles, and may likewise be used with receptacles not provided with a flap by inverting the fastener 13 and securing it to the inner side of one of the side walls and slotting the other side wall after which the container can be closed by lifting up on the slotted wall to pass the upper slotted end over the points 21 and said wall moving downwardly when released thereby preventing the slotted wall from becoming disengaged from the members 19 until it is again raised relatively thereto.
10. Various modifications and changes in the construction and arrangement of the parts forming the invention may obviously be made and are contemplated, and the right is reserved to make such variations and changes as do not depart from the spirit and scope of the invention as hereinafter defined by the appended claims.
15. I claim as my invention:
20. 1. A device of the class described comprising a flat container provided with a closing flap having a transverse slot formed therein intermediate of its ends, a fastening member, comprising a pair of flat complementary sections in substantial contact arranged in vertical planes perpendicular to the container, said sections having downwardly sloping upper edges and tapered converging lower edges, said flap being adapted to be pulled downwardly to permit said sections to be passed through the slot, said flap in its normal position

being held by said fastening member by engagement of the portion beneath said slot with the lower converging ends of said sections.

2. In a device of the class described, a blank having end portions forming a base, the intermediate portion of said blank being cut to form two notches along its upper edge and four points along the lower edge, said intermediate portion being foldable between said points to form a pair of corresponding flaps, pointed at their lower ends and bevelled on their upper ends.

3. A device as in claim 2, said base being adapted to be secured to the back of a paper container provided with a closing flap having a slot, and the flaps of said blank being passed through said slot and adapted to engage the lower portion of the container flap to secure it to the back of the container.

4. In combination with a container having a closing flap provided with a slot, fastening means for said flap comprising a blank having end portions forming a base, the intermediate portion of said blank being folded to provide corresponding retaining elements projecting outwardly from said base portions said retaining elements having outwardly and downwardly inclined top and bottom edges, said base portions being adapted to be secured to the back of the container with their adjacent edges in substantially abutting relationship, and said retaining elements being adapted to be passed through said slot, the lower end of said slot normally engaging the inclined bottom edges of said retaining elements to hold the flap in a closed position.

IRENE W. MABRY.
